FIG. 1.

FIG. 2.

FIG. 3.

J. M. Clark,

INVENTOR

BY *Victor J. Evans*

ATTORNEY

UNITED STATES PATENT OFFICE.

JOSEPH M. CLARK, OF APOLLO, PENNSYLVANIA.

WRENCH.

1,398,889.

Specification of Letters Patent. Patented Nov. 29, 1921.

Application filed June 3, 1921. Serial No. 474,743.

To all whom it may concern:

Be it known that I, JOSEPH M. CLARK, a citizen of the United States, residing at Apollo, in the county of Armstrong and State of Pennsylvania, have invented new and useful Improvements in Wrenches, of which the following is a specification.

This invention relates to wrenches, and more particularly to a multiple armed wrench which may be used in connection with socket members, or may be applied directly to nuts which it is desired to apply or remove.

One of the main objects of the invention is to provide a wrench of the character stated having a plurality of sockets of varying sizes and means for rendering any one of the sockets, selectively, available for use. A further object is to provide a wrench of this character in which any one of the socket members may be readily replaced, and which may be readily assembled or disassembled for cleaning, repairs, or other purposes. Further objects will appear from the detailed description.

In the drawings:—

Figure 1 is a plan view, partly in section, of a wrench constructed in accordance with my invention.

Fig. 2 is an end view.

Fig. 3 is a detail of one of the latch members.

The body of the wrench is of T-shape and includes a stem 1 upon which is threaded a head 2 by means of a neck 3, the head being secured against rotation upon the stem by a set screw 4. An outer socket member 5 is threaded upon each end of head 2, and is secured against rotation upon the head by a set screw 6. A rod 7 is slidably mounted in a bore extending through head 2, and this rod is provided at one end with a socket member 8 which fits snugly within socket member 5 and is threaded upon rod 7. As the socket members 5 and 8 are both of hexagonal cross-section, rotation of member 8 is prevented so that this member cannot become detached from rod 7. A second socket member 9 is detachably secured by a screw 10 upon the other end of rod 7, and fits snugly within socket member 5 at the other end of head 2. As will be more clearly noted from Fig. 1, the socket members 8 and 9 are of less length than the socket members 5 so that by moving the rod 7 into its extreme position in either direction one of

the socket members 5 is rendered available for use at one end of the head, and one of the socket members 8 or 9, as the case may be, is available for use at the other end of the head. A screw 10^a is threaded into rod 7 at the longitudinal center thereof, and the head 11 of this screw projects through a slot 12 formed in head 2 of the wrench and fits snugly between fingers 13 at one end of stem 14 of the latch member 15, the latch member being pivoted to the screw by a pin 13^a. Body 16 of this member is provided with a groove 17 at its outer end, which is adapted to receive the outer portion of the inclined wall 18 at either end of slot 12. When the rod 7 is moved into its extreme position in either direction, latch member 15 is depressed so as to be secured against accidental displacement by wall 18, thus locking the rod 7 in position.

Stem 1 is provided with a central bore in which is slidably mounted a rod 7^a corresponding to rod 7 and provided at its outer end with a socket member 5^a detachably secured on rod 7^a by means of a screw 10^b. Socket member 5^a fits snugly within an outer socket member 5^b threaded upon the outer end of stem 1 and secured in adjustment thereon by set screw 6^a. As will be noted more clearly from Fig. 1, socket member 5^a is of approximately one-half the length of socket member 5^b so that by adjusting the rod either socket member, optionally, may be rendered available for use. For securing rod 7^a in adjustment I provide a latch member 15^a similar to latch member 15, which is pivoted on a screw 10^c threaded into rod 7^a, this latch member 15^a co-operating with inclined walls similar to walls 18 for locking rod 7^a in longitudinal adjustment.

In practice the inner and the outer socket members are all of different sizes so that the wrench will take six different sizes of nuts, and any of the socket members desired may be quickly and easily rendered available for use. As will be understood, this wrench may be applied directly to the nuts which it is desired to remove or apply, or may be used in connection with socket members in the same manner as the ordinary socket wrench.

What I claim is:—

In a wrench of the character described, a T-shaped body, outer socket members secured on the ends of the head of the body,

an outer socket member secured on the outer end of the stem of the body, a rod slidably mounted in said head, inner socket members secured on the ends of said rod and slidable in the outer socket members of the head, means for securing said rod in adjustment, a rod slidable in said stem, an inner socket

member secured on the outer end of said rod and slidable in the outer socket member of the stem, and means for securing the second mentioned rod in longitudinal adjustment.

In testimony whereof I affix my signature.

JOSEPH M. CLARK.
